John B. Connolly.
Design for a bushador.

22942

PATENTED
MAR 3 1868

Geo. W. Walker
Chas. Smith

John B. Connolly

United States Patent Office.

JOHN P. CONNOLLY, OF RAVENSWOOD, NEW YORK.

Design No. 2,942, dated March 3, 1868.

DESIGN FOR A CUSPADOR.

The Schedule referred to in these Letters Patent and making part of the same.

TO ALL WHOM IT MAY CONCERN:

Be it known that I, JOHN P. CONNOLLY, of Ravenswood, in the county of Queens, and State of New York, have invented or produced a new and original Design for a Cuspador; and I do hereby declare the following to be a correct description of the same, reference being had to the annexed drawing, making part of this specification, wherein I have shown an elevation of said cuspador.

The article to which my said design relates has heretofore been made in the shape of a bowl or urn, and used for the reception of scraps of paper, burnt matches, and other refuse matter in parlors, sitting-rooms, and other parts of houses, but the shape has been such that it was easily upset. The aforesaid article has been known in the trade as a "cuspador."

My improvement consists in the design of the shape or ornamental configuration of the said cuspador; and I here remark that my said article may be used as a spittoon.

The general shape of my cuspador is round and hollow. It is formed with a broad base, *a*, above which is a cove, *b*, and a compound curve or "ogee," *c*, to the neck-band *d*, above which, the flaring mouth or flange *e* is formed. The color or painted surface ornamentation forms no part of my design, neither does the material of which said cuspador is made.

What I claim, and desire to secure by Letters Patent, is—

The design of the shape and configuration of the said "cuspador," substantially as represented in the drawing.

In witness whereof, I have hereunto set my signature, this third day of February, 1868.

JOHN P. CONNOLLY.

Witnesses:

CHAS. H. SMITH,

GEO. D. WALKER.
